HOT WATER HEATING SYSTEM

David E. Morgan, Westmont, N. J., assignor to Warren Webster & Company, Camden, N. J., a corporation of New Jersey

Application May 12, 1955, Serial No. 507,852

9 Claims. (Cl. 237—8)

This invention relates to heating systems and more particularly to such systems of the type wherein hot water as the heating medium is circulated to and from the radiating units by a circulating pump which is started and stopped at varying intervals under the control of a thermostat, and so as to circulate the hot water to and from a boiler.

This application comprises a continuation-in-part of my copending application, Serial No. 447,033, filed August 2, 1954, now forfeited, and entitled Hot Water Heating System.

Although such circulating hot water systems have long been in use, one of the disadvantages thereof has been that on each occasion when the circulating pump is started to circulate hot water through the relatively cold radiating system, the resulting rapid expansion of the piping, radiators and the radiating fins causes annoying snapping, "pings" and "chunk" noises. Similar troublesome noises also occur to some extent on each occasion when the circulation is stopped and the system rapidly cools.

Another difficulty with such systems has been that in relatively mild or warm weather, when only a small amount of heating is required, the pump will come into action only at widely spaced intervals for short periods, but during each of such periods the radiating system will be quickly brought up to a temperature which will be excessively high as compared to what would be desirable, or if steps are taken to avoid that result then the system becomes inefficient in meeting the requirements during the coldest weather. With such widely spaced intervals of heating of the circulating water, its maximum temperature during the "on" intervals may exceed, for example, 200° F. so that when the thermostat acts to stop the circulating pump, there will be so much excess heat available in the radiators and the water therein, that the ensuing "off" period will be prolonged, and while the actual room temperature may remain reasonably close to the desired value during the "off" intervals, yet the radiators will have time to become so cool that they will not give off radiant energy but will in effect absorb radiant energy from the atmosphere in the room and from the occupants so that a condition will exist which is sometimes referred to by heating experts as a "cold 70°" temperature. In short, although the temperature of the room atmosphere may remain reasonably close to the desired level, yet the water temperature in the radiators will fluctuate through a range, for example, of more than 125° F., which gives rise to a feeling by the occupants of pronounced alternate cooling and heating.

Attempts to secure more uniform heating have included use of well-known forms of so-called "anticipating" thermostat arrangements such that the thermostat will be actuated to start an "off" period somewhat prior to the rise of the room temperature to the actual desired maximum level, such thermostats also being so adjusted as to start the "on" intervals somewhat prior to the lowering of the room temperature to its minimum level. But while such anticipating thermostats tend to regulate the room

temperature more closely to a predetermined value, they have no substantial effect upon reducing the wide variations of the temperature in the circulating water itself, and thus the alternate sensations of overheating and excessive cooling due to radiant energy effects are still felt by the room occupants.

Heretofore with such systems, it has been rather common practice to provide between the hot water outlet of the boiler and the return water inlet to the boiler, a by-pass conduit so that the circulating pump will not cause all of the water which is circulated through the radiating system to be returned to the boiler and so that the water which is forced out to the radiating system will comprise, in part, hot water coming directly from the boiler and in part relatively cooler water which has been returned from the radiating system and is mixed with the hot water by way of such by-pass. With such a by-pass, each time when the circulating pump is started there will be a slight delay before the water circulating in the radiating system reaches its maximum temperature, and the circulated water will be at a temperature somewhat lower than the boiler water temperature, these results being due to the fact that the circulated water comprises a mixture of hot boiler water and relatively cool returned water coming through the by-pass. Thus while such a by-pass, to some extent, diminishes the problem of momentarily excessively hot radiators during mild weather, it tends to prevent flow of a sufficiently hot stream to insure most efficient cold weather heating. And while the use of the conventional by-pass causes a slight delay in bringing the circulating water up to the desired temperature each time the pump starts, yet such minor delay has in practice been found insufficient to minimize to any noticeable degree the above-described noise troubles. Even if such a by-pass conduit is made with the most desirable size for the purpose, the circulating water temperature during "on" and "off" periods will still vary within such a wide range as to give occupants alternate sensations of overheating and excessive cooling and the difficulty will remain even though the above-described anticipating types of thermostat arrangements are used.

The present invention involves a means and method for avoiding or substantially minimizing the above-noted difficulties in a relatively simple, reliable and inexpensive way, whereby the variations in the circulating water temperature during the "on" and "off" periods may be kept within a quite narrow range, thereby avoiding the troublesome noise effects and at the same time giving the room occupants a feeling of quite uniform heating.

According to the present invention, a by-pass as above described is used, preferably one which has a predetermined and relatively small or somewhat restricted passage. At the point where the by-passed water mixes with the outgoing hot boiler water, a heat-responsive valve operating device is inserted, this device being connected to operate a valve which controls the flow of the outgoing hot boiler water. (In some cases, but not preferably, this valve alternatively might be located at the juncture of the by-pass and the return line to the boiler.) The valve element has a small aperture or apertures, or an equivalent by-pass, through which at least a small quantity of the hot boiler water may flow whenever the pump is operating and even though the valve may otherwise be closed so far as normally possible. Thus when the circulating pump is initially started, it will cause a small amount of hot boiler water to flow through such valve apertures or the equivalent and be mixed with a small stream of returned cooled by-pass water, and thus for a period of from five to ten minutes, for example, the water circulated through the radiating system will be of moderate temperature suitable for mild weather heating, and if the weather is mild the circulating pump will be stopped

by its thermostat before the radiating system is excessively heated. Furthermore, the radiating system during this period will only gradually become heated and the troublesome noises will be avoided or eliminated. However, if the weather is cold enough to require operation of the pump for a longer interval, then after such period of five or ten minutes, the circulated water in the radiating system will have reached a temperature such as to operate the above-mentioned heat-responsive valve means thereby opening the valve which it controls, to the extent necessary for allowing a larger stream of hot water to come from the boiler and mix with the returned by-pass water thereby bringing the radiating system up to the necessary higher temperature for cold weather heating. But since the heating of the radiating system has been gradual, there will still be no sudden application of hot water to relatively cool metal parts and as a consequence the troublesome noises will be largely avoided or eliminated.

Usually to secure the most satisfactory results from the above-described special heat-responsive valve and by-pass, one should use the above-described anticipating type of thermostat arrangement or the equivalent. While without such special valve and by-pass the anticipating thermostat arrangements have no substantial effect toward minimizing the fluctuations in the circulating water temperature, yet with such special valve and by-pass means, the anticipating thermostat means will permit the water temperature to be confined to an exceptionally narrow range, for example, from about 8° in a typical case in cold weather up to about 10-20°, for example, in warmer weather, the position of such range on the temperature scale shifting automatically according to the heating requirements and the range being high enough to insure that some heat will always be given off by convection as well as radiation.

Preferably, a valve is inserted in the boiler water outlet connection in advance of the connection to the by-pass, which valve is of a construction adapted to open only when the circulating pump causes a flow under pressure to occur therethrough, this valve at other times remaining closed to prevent gravity circulation of water through the system at times when the thermostat does not call for operation of the circulating pump.

Other and more specific objects, features, and advantages of the invention will appear from the detailed description given below, taken in connection with the accompanying drawings and forming a part of this specification and illustrating by way of example the presently preferred embodiments of the invention.

In the drawings:

Fig. 1 is a diagram schematically showing a boiler and associated heating system including the combinations of features involving the present invention;

Figs. 1a-1e, inclusive, are schematic diagrams showing various possible alternative arrangements for the connection of the various units of the system;

Fig. 2 is a vertical sectional view through the special device or heat-responsive valve means located at the junction of the hot water outlet conduit coming from the boiler and the by-pass connection;

Fig. 3 is a sectional view taken substantially along line 3-3 of Fig. 2;

Fig. 3a is a side view on a smaller scale of a valve assembly like that of Fig. 2, except having a by-pass permitting a limited flow past the valve in lieu of utilizing valve apertures as of Fig. 3 for that purpose;

Fig. 4 shows certain time-temperature curves indicating the temperature conditions of the circulating water with and without the present invention; and

Fig. 5 shows portions of a circular type temperature recorder dial or graph and indicating an actual example of the circulating water temperature range secured by the use of the invention over a period starting at 6 o'clock

on one evening and ending thirty-six hours later, the current room temperatures and outdoor temperatures for this period also being indicated.

Referring to Fig. 1 in further detail, a boiler is indicated at 10 provided with any well-known form of fuel burner as indicated at 11 which operates under the control of a boiler thermostat schematically indicated at 12 whereby generally the boiler water will be maintained at a suitable substantially constant predetermined temperature. The hot water outlet conduit from the boiler is indicated at 13, and to which a conventional expansion tank is connected as indicated at 13a. If desired, the expansion tank construction and arrangements may be used as disclosed in the co-pending application of David E. Morgan and James E. Tolan, Serial No. 378,512, filed September 4, 1953. Conduit 13 includes a valve 14 of a suitable known type having a valve-piece which will normally be closed as by gravity to prevent any gravity flow of water through the system when the circulating pump is not operating. From the valve 14 the hot water next flows into a device or valve 15, such as shown in further detail in Fig. 2. From the device 15 connections are provided, such as shown at 16, 17, 18, etc., for conducting the hot water to the various radiators, as indicated at 17', 18', 19', etc., each radiator being provided with a return connection communicating with return lines as at 20, 21, 22, running to an air elimination device at 22' of any suitable known type, thence to an electric motor-driven pump 23. This pump discharges the return water through a conduit 24, partially into a by-pass connection 25 and partially into a return connection 26 into the boiler.

The pump is controlled in a known way by a room thermostat 27 connected by means of a relay 27' to control the circuit of the pump motor so as to start such motor whenever the room temperature decreases to a predetermined point and to stop the motor when the room temperature rises again to a predetermined degree. As above indicated, this thermostat arrangement is preferably of the type which is herein referred to as an "anticipating thermostat." That is, in series with the contacts of the thermostat 27 and with the coil 28 of relay 27', an adjustable heating resistance 29 is connected. Assuming that the thermostat contacts are in closed position during an "on" interval of operation of the circulating pump, then the resistance 29 will cause sufficient heating of the bimetallic strip of the thermostat 27 to cause the contacts to open shortly before the maximum desired room temperature is reached, that is, in anticipation of such maximum temperature. Also, the thermostat contacts are so adjusted that during an "off" interval of operation of the circulating pump, such contacts will remain open only until the room temperature decreases to a value slightly above the intended minimum room temperature, thus causing the next "on" interval to start in anticipation of the minimum room temperature. Generally the resistance 29 is so made or adjusted as to have about the same value as the resistance of the remainder of the circuit, viz., largely that of the relay coil 28. But with the present invention, preferably although not necessarily, the resistance 29 is made adjustable whereby, as will be hereinafter made apparent, the range of fluctuations of the circulating water temperature may be varied. That is, simply by moving the adjustable contact on resistance 29 to include in the circuit less resistance, one may with the system of this invention limit and decrease the circulating water temperature range; or by moving such contact so as to include in the circuit more resistance, one may secure a wider water temperature range.

The radiators may be of any suitable known type, for example, some may be of the conventional cast iron type such as at 17', 19', or some or all may be of the finned tube type as at 18'.

The by-pass connection 25 preferably comprises a pre-

determined length of tubing, for example, ten feet of relatively flexible copper tubing of a diameter generally smaller than the other piping, for example $\frac{5}{8}$ inch O. D. In order that the restrictive effect of the by-pass may be made uniform for different installations regardless of the space available between the device 15 and the return line to the boiler, such by-passes may be formed of tubes of the above-stated length and any available excess of the tubing in particular installations may be coiled as at 25a.

Referring now to Fig. 2, the device 15 may comprise a T-shaped coupling connected at one side to the hot boiler water outlet conduit 13 and at the other side to the outgoing pipe of the circulating system; the third branch of the T being directed downward and connected to the by-pass 25. Within the mid-portion of the body of this coupling there is located a heat-responsive valve actuator 39 of some suitable known type, for example, a construction operating according to the principles disclosed in U. S. patent to Vernet, No. 2,115,501. However, it will be understood that various other known types of heat-responsive valve operating devices may be used for the purpose, same being connected to the actuated valve element, such as a butterfly type of valve-piece 31, which normally when closed is positioned in a vertical plane and has apertures 32 therethrough to allow some hot water from the boiler to pass even when the valve otherwise is closed. Alternatively, instead of forming the valve-piece itself with apertures as at 32, it will be appreciated that an equivalent might be provided by so constructing or adjusting the valve-piece or its actuator that the valve will never entirely close but will allow a small stream to by-pass the valve-piece even when thrust as far as it will move toward closed position. Or, alternatively, a small by-pass as at 32' in Fig. 3a might be used instead of apertures 32. A fixed orifice or adjustable valve at 38 may be provided for controlling or varying the flow through the by-pass 32'. The heat-responsive element 30 and the valve-piece may be formed as a unitary assembly and insertable into the body of the device 15 in the position shown and then removably clamped in place as by the use of a nipple 33 and a threaded ring or annular clamping nut 34. A gasket 35 is provided between nipple 33 and the peripheral flange 36 on the valve assembly. Preferably, in order to insure that the valve apertures 32 will be located at a predetermined position at the upper-side remote from the by-pass 25, the assembly flange 36 is provided with a pin, or the like, 37 for engaging in a corresponding hole formed in the body of the device 15.

The operation of the system according to the invention will now be briefly reviewed. Assuming that the room temperature falls to a degree such as to soon require heat, then the thermostat 27 will act through relay 27' to close the pump motor circuit and water will be pumped from the radiator system through the air-eliminator 22', thence through the pump 23, thence partly through the by-pass 25 and partly through the return pipe 26 into the boiler. Then hot water at a limited rate of flow will be forced out of the boiler through connection 13, valve 14 and through the valve apertures 32 (or the equivalent) into the mid-portion of the device 15. At this point, this limited amount of hot boiler water will mix with the cool water returned through the by-pass 25 and the resulting mixture of intermediate temperature will be forced out through the radiating system and back to the pump. But after, for example, five or ten minutes the mixture as circulated through the radiating system will have increased in temperature enough, so that when mixed with additional hot boiler water coming through apertures 32, it will cause actuation of the heat-responsive means 30 and opening of the valve 31. However, if before this happens, the room temperature has risen enough to actuate the ther-

mostat 27, the pump will be stopped with consequent stoppage of circulation of hot water through the radiating system. At the same time valve 14 will automatically close to prevent further flow of hot water to or from the boiler by the action of gravity. In any event, the radiating system and its conduits will have become heated rather gradually over a period of a number of minutes so that the troublesome noises due to rapid expansion of the metal are minimized or eliminated. And if the valve 31 does not open before the thermostat 27 stops the pump, then the radiating system will not have become heated, even momentarily up to any excessive temperature such as would normally only be required in cold weather.

On the other hand, if the weather is cold enough so that the thermostat 27 causes the pump to remain in operation until the valve 31 is opened after five or ten minutes, then as this valve opens more and more, hot water at an increasing rate will be forced from the boiler into the device 15 and the cooler water from by-pass 25 will constitute a smaller and smaller percentage of the mixture which is circulated through the radiators, the percentage depending upon the degree to which valve 31 becomes opened, which in turn depends upon the required length of the heating cycle during cool or colder weather. Finally, when the room temperature reaches a level causing the thermostat 27 to stop the pump motor, then the valve 14 will close to prevent further circulation of hot water from the boiler by the action of gravity and the valve actuating device 30 will gradually cool and move the valve 31 to closed position ready for another cycle of operation, as above described.

Thus, in any case, changes of temperature in the metal parts of the circulating system will always be fairly gradual and the troublesome noises will be minimized or eliminated. In addition, valve 31 in the device 15 will act to provide for low temperature water circulation in mild weather and substantially higher circulating water temperatures of the degree required during cool or colder weather.

Fig. 5 shows the results of an actual test of the system over a typical period of thirty-six hours during which the room temperature was retained substantially constant, that is, in a narrow range just below 75 degrees, as indicated, 35 while the outdoor temperature, as also shown, fell from about 56 degrees to about 28 degrees. Throughout this time, as shown by the upper fine zigzag curve, the circulating water temperature in the radiating system (as measured in the pipe running to the radiators) was kept within a range of from about 8 to 20° F., the median value gradually increasing by amounts corresponding to the gradual decrease of the outdoor temperature and the range gradually decreasing with colder weather. Thus, although the system operates to provide heat with "on" and "off" intervals, the effect is similar to what would be attained if the circulating water flowed continuously at a gradually varying temperature corresponding inversely to the gradual variations of the outdoor temperature, the only exception to this effect being that during the "on" and "off" intervals, the water temperature varies above and below a median level by some 4 to 10 degrees. This amount is insufficient to allow the radiating system ever to even approach a cold condition or to be heated sufficiently rapidly or over a sufficient range to give rise to the troublesome noises. At the same time there is no excessive heating of the radiators when the weather is mild, or excessive cooling of the radiators even for momentary intervals when the weather is cold.

The advantages of the invention may be appreciated from the following facts. If the water temperature curve of Fig. 5 were for a conventional circulating hot water heating system of the "on" and "off" type with no boiler by-pass, then such curve would zigzag between points in the neighborhood of 200° F. down to room temperature or possibly less. And if the system were one with a well-

designed boiler by-pass but without the thermostatically controlled valve as at 15 herein disclosed, then this water temperature curve would ordinarily zigzag over an intermediate wide range, say of 100° F. or more, and the result would be the same whether or not an anticipating type of thermostat arrangement were used. The troublesome noisy conditions would occur as would also the "cold 70 degree" sensations during "off" intervals. With the by-pass 25 accompanied by the special thermostatic valve 15, but without an anticipating type thermostat, the zigzag range of the water temperature would be considerably more limited than with either of the other two above-mentioned conditions. But with the anticipating thermostat added, the upper and lower temperatures of the circulating water may be not only brought substantially closer together, but the degree of closeness thereof may be very easily adjusted by simply adjusting the contact on resistance 29. While it is desirable to keep the water temperature range within as narrow limits as possible, yet if the range is made too narrow, then the frequency of starting and stopping of the circulating pump may become excessive or annoying, particularly when the outdoor temperature is colder. With the example of the water temperature curve shown in Fig. 5, there are about six "on" periods per hour at the time of the start of the test, whereas during the colder and later periods of the test, the number of such periods per hour increased considerably and with a consequent narrowing of the range of water temperatures. The more abrupt changes in the water temperature range indicated in Fig. 5 occurred as a result of opening doors or windows, yet it will be noted that the room temperature remained substantially constant.

In Fig. 4, the full line curve shows the results of an actual test and indicates the rate at which the circulating water temperature rises, upon starting the pump, to a maximum with delayed action over a period of about nine minutes, when the boiler water temperature is at the predetermined regulated temperature of about 210 degrees or slightly less. The dash line curve in Fig. 4 on the other hand shows the temperature changes which will occur without the combination of the invention, that is, in a system the same as of Fig. 1 but without the temperature responsive valve means in the device 15. Here it will be noted that immediately upon starting the circulating pump, the hot boiler water will be forced into the outgoing conduits of the radiating system, thus filling at least portions thereof with water at substantially the maximum temperature almost immediately and causing thermal shocks and consequent noises throughout the radiating system. Then when relatively cold recirculated water has replaced the hot water in the boiler, and also through the by-pass, has become mixed with the out-going boiler water, the temperature of the outgoing circulated water will drop sharply again approximately as indicated by the dash line curve, causing further thermal shock and noises before the boiler water and the circulated water gradually increase again in temperature. These conditions, approximately as shown by the dash line curve of Fig. 4, will thus cause two noisy intervals for each cycle of operation of the pump, when the present invention is not used. It should be further noted that preferably the dimensions of the by-pass 25 should be so related to the size of the apertures 32 in the valve 31 that the resistance to flow through these passages will have a predetermined relationship. For example, with a preferred embodiment of the invention, the three apertures 32 were made circular with diameters of about $\frac{5}{32}$ ", whereas the by-pass 25 as above-mentioned was made of a length of tubing 10 feet long and having an internal diameter of about 0.545" ($\frac{7}{16}$ " O. D. copper tubing). With these relative dimensions and with the boiler outlet pipe 13 made of 1" or $1\frac{1}{4}$ " piping (standard iron pipe sizes), it was found that when the valve 31 was closed, about 40% of the flow to the heating system would pass through the valve apertures 32 and the remaining 60% through the by-pass. These relative percentages of

flow may, of course, be varied considerably, as may also the pipe and aperture dimensions above given, while still achieving substantially the above-described advantages.

It should be further noted that preferably all portions 5 of the pipe 13 between the boiler and the valve 15 should, as indicated in Fig. 1, be directed upwardly from the boiler or inclined at least somewhat upwardly toward the valve 15. This will insure that any bubbles of air which may be contained in this pipe will pass on through the 10 valve apertures 32 which are located on the upper side of valve-piece 31. Thus the entrapment of air at any point in advance of the valve 15 will be avoided.

The system of the invention has an additional advantage useful in some instances and which has not been mentioned above. With many household heating systems, provision is made for obtaining domestic hot water by the use of a water heater at the boiler. With such systems, it is sometimes the practice to provide a "reverse acting" control for the circulating pump so as to prevent 20 actuation of the pump and the heating of the house when the boiler water temperature falls below a certain point, for instance 160° F. This allows the burner to raise the boiler temperature again quickly and to assure that the necessary supply of domestic hot water can properly be 25 heated for a time by the boiler. During this time, of course, the house will not be heated because the circulating pump is not in operation. However, with the present invention, such a "reverse acting" control on the circulating pump will not ordinarily be necessary because when 30 the boiler water temperature tends to be rather low, the heat-responsive valve-actuating device 30 will not operate to open the valve 31. Accordingly, the house heating system may be kept in operation to at least provide some 35 degree of heat without allowing enough hot water to be taken from the boiler to prevent the latter from heating the domestic hot water supply at times when necessary, and then to permit the boiler temperature to rise to normal.

In different installations, the heat-responsive devices 40 30 may be selected or adjusted so as to start opening valves 31 at different predetermined temperatures depending upon the normal predetermined regulated temperature level in the boiler. Usually, the device 30 may be 45 adjusted or selected to actuate at 150°, 160° or 170° F., corresponding respectively to the three common ranges of boiler water temperatures customarily used.

Although the locations of the various units of the system are preferably as per Fig. 1, satisfactory operation or at least improved results may be secured with the 50 various other arrangements as shown in Figs. 1a to 1e, inclusive, wherein corresponding parts are identified by the same reference numerals as in Fig. 1. For example, in Fig. 1a the circulating pump 23 is indicated as being located either in the boiler water outlet or as at 23a in the outgoing conduit running to the radiators. That is, either one of the pumps as at 23 or 23a may be used while the other one is inactive with the water passing therethrough without being pumped, or either one of these pumps may be omitted. In Fig. 1b the special thermostatic valve 15 is located at the juncture of the pipe returning from the radiators with the lower end of the by-pass 25, the circulating pump being located as in Fig. 1a. Fig. 1c is the same as Fig. 1b except that the circulating pump is located as in Fig. 1. Fig. 1d shows a system like that of Fig. 1, but with separate outgoing and return connections for five different heating zones, as may be necessary or desirable, for example, in a large building. Fig. 1e shows another arrangement with separate devices and circulating pipes in outgoing conduits for five heating zones from which a single return connection 24 is 60 provided.

Although certain preferred embodiments of the invention are herein disclosed for purposes of explanation, various modifications thereof, after study of this specification, will be apparent to those skilled in the art to which

the invention pertains. Reference should accordingly be had to the appended claims in determining the scope of the invention.

What is claimed and desired to be secured by Letters Patent is:

1. In a circulating hot water heating system, the combination comprising a boiler, means for maintaining the boiler water heated to a desired normal degree, conduit means for conducting hot water from the boiler through a radiating system and including a return connection back into the boiler, said conduit means including therein a motor-driven circulating pump, thermostatic means for starting and stopping said motor-driven pump responsive to temperature changes, a relatively restricted boiler by-pass having one of its ends connected into said return connection and having its other end connected into a device through which the outgoing hot boiler water passes to the radiating system, said device having therein a heat-responsive valve-actuating means located in a position to be responsive to a predetermined temperature of the mixture of hot water coming from the boiler and cooler return water from the by-pass, and a valve operatively connected to said actuating means, said valve being positioned normally to check the flow of hot water from the boiler into said device but being arranged with a restricted passage means permitting at least a limited flow of hot boiler water to normally pass when the pump is operating, for admixture with the returning by-passed water, and whereby after a period of delay following the starting of the pump, the resulting mixture will rise to said predetermined temperature and cause said heat-responsive device to open said valve to allow a greater proportion of hot boiler water to be circulated through the heating system during the remainder of the interval of operation of the pump, such delay affording time for the radiating system to be gradually heated by a relatively low temperature water mixture before the valve is opened widely for providing higher temperature heating, rapid thermal expansion and consequent noises in the heating system being thereby substantially reduced.

2. In a circulating hot water heating system, the combination comprising a boiler, conduit means for conducting hot water from the boiler through a radiating system and including a return connection back into the boiler, said conduit means including therein a motor-driven circulating pump, thermostatic means for starting and stopping said motor-driven pump responsive to temperature changes, a boiler by-pass having one of its ends connected into said return connection and having its other end connected into a device through which the outgoing hot boiler water passes to the radiating system, said device having therein a heat-responsive valve-actuating means located in a position to be responsive to a predetermined temperature of the mixture of hot water coming from the boiler and cooler return water from the by-pass, and a valve operatively connected to said actuating means, said valve being positioned normally to check the flow of hot water from the boiler into said device but being arranged with a restricted passage means permitting at least a limited flow of hot boiler water to normally pass when the pump is operating, for admixture with the returning by-passed water, whereby after a period of delay following the starting of the pump, the resulting mixture will rise to said predetermined temperature and cause said heat-responsive device to open said valve to allow a greater proportion of hot boiler water to be circulated through the heating system during the remainder of the interval of operation of the pump, such delay affording time for the radiating system to be gradually heated before said valve is widely opened.

3. In a circulating hot water heating system, the combination comprising a boiler, conduit means for conducting hot water from the boiler through a radiating system and including a return connection back into the boiler, said conduit means including therein a motor-driven cir-

culating pump, thermostatic means for controlling said motor-driven pump at intervals responsive to temperature changes in a space to be heated, a boiler by-pass having its ends connected respectively into the outgoing and return connections of the system, one of said ends being connected into a device through which the circulating water passes, said device having therein a heat-responsive valve-actuating means located in a position to be responsive to a predetermined temperature of the mixture of circulated water and by-pass water, and a valve operatively connected to said actuating means, said valve being positioned normally to check the flow of circulating boiler water but being arranged with a restricted passage means permitting at least a limited flow of circulating water normally to pass whenever the pump is operating, whereby after a period of delay following the starting of the pump the said mixture will rise to said predetermined temperature and cause said heat-responsive device to open said valve to allow a greater proportion of hot water to be circulated through the heating system while the pump remains in operation.

4. Apparatus according to claim 1 and in which an additional valve is located in the hot water outlet conduit from the boiler, which additional valve is constructed and arranged to be normally closed when the pump is not operating, to prevent circulation of water through the system by the action of gravity, but to be automatically opened by the flow of water when the pump is operating.

5. In a circulating hot water heating system, the combination comprising a boiler, conduit means for conducting hot water from the boiler through a radiating system and including a return connection back into the boiler, said conduit means including therein a motor-driven circulating pump, an anticipating thermostatic arrangement for controlling said motor-driven pump to start and stop the same at intervals responsive to temperature changes in the spaces to be heated, a boiler by-pass having its ends connected respectively into the outgoing and return connections of the system, one of said ends being connected into a device through which the circulating water passes,

40 said device having therein a heat-responsive valve-actuating means located in a position to be responsive to a predetermined temperature of the mixture of circulated water and by-pass water, and a valve operatively connected to said actuating means, said valve being positioned normally to check the flow of circulating boiler water but being arranged with a restricted passage means permitting at least a limited flow of circulating water normally to pass whenever the pump is operating, whereby after a period of delay following the starting of the pump the said mixture will rise to said predetermined temperature and cause said heat-responsive device to open said valve to allow a greater proportion of hot water to be circulated through the heating system while the pump remains in operation.

6. In a circulating hot water heating system, the combination comprising a boiler, conduit means for conducting hot water from the boiler through a radiating system and including a return connection back into the boiler, said conduit means including therein a motor-driven circulating pump, thermostatic means for controlling said motor-driven pump to start and stop same at intervals responsive to temperature changes in the space to be heated, said thermostatic means including a thermostatic contact actuating element accompanied by a heating resistance for causing actuation of the thermostat and consequent stopping of the pump in anticipation of the approach of the space temperature to its desired maximum value, a boiler by-pass having its ends connected respectively into the outgoing and return connections of the system, one of said ends being connected into a device through which the circulating water passes, said device having therein a heat-responsive valve-actuating means located in a position to be responsive to a predetermined

11

temperature of the mixture of circulated water and by-pass water, and a valve operatively connected to said actuating means, said valve being positioned normally to check the flow of circulating boiler water but being arranged with a restricted passage means permitting at least a limited flow of circulating water normally to pass whenever the pump is operating, whereby after a period of delay following the starting of the pump the said mixture will rise to said predetermined temperature and cause said heat-responsive device to open said valve to allow a greater proportion of hot water to be circulated through the heating system while the pump remains in operation.

7. A circulating hot water heating system embodying the combination specified in the foregoing claim 5 and in which the anticipating thermostatic arrangement includes an electrical heating element for applying heat to cause actuation of the thermostatic means and consequent stopping of the pump in anticipation of the desired maximum temperature in the space being heated, said heating element being adjustable to thereby permit adjustment of the range within which the temperature of the circulating water varies during the intervals of starting and stopping of the pump.

8. A circulating hot water heating system embodying the combination specified in the foregoing claim 5 and in which the thermostatic arrangement includes a thermo-

12

static contact actuating element, an electrical heating element adjacent said operating element, a relay for controlling the pump motor circuit, said relay having a winding in series with said heating element and the thermostat contacts.

9. A device for controlling the flow of water in a circulating hot water heating system having a boiler by-pass, said device comprising a valve chamber with a main inlet and a main outlet for the circulating water and also means for connecting into same one end of the boiler by-pass, a heat-responsive valve actuating means in said chamber and located in a position to be responsive to a predetermined temperature of the mixture of circulated water and by-pass water, and a valve in the chamber operatively connected to said actuating means, said valve being positioned normally to check the flow of boiler water but being arranged with a restricted passage means permitting at least a limited flow of circulating water normally to pass when said actuating means is inactive.
